LOUIS A. SHERMAN, OF GROSSE POINTE, MICHIGAN

PERMANENT SHIPPING RACK

Application filed June 23, 1927. Serial No. 200,844.

This invention has to do with the crating and shipping or otherwise handling of articles.

The invention is devoted particularly to the provision of a permanent shipping rack which, after use, is to be returned to the shipper to be used over again. It has been the practice to ship articles by utilizing wood crating. The use of wood crating represents an outlay of time in making the crating, and wood once used is not suitable for use again, so that the cost of the wood crating represents a considerable overhead to the shipper. The present invention contemplates a permanent shipping rack, or frame, made largely of metal. This rack will perhaps be somewhat more expensive than a crate of wood, but due to the fact that it can be used over and over again it will, in the long run, be cheaper than wood crating.

Moreover, the invention is concerned with the shipping of articles which are relatively delicate and liable to be broken or otherwise made defective by the abuse to which it is subjected while in the crating and being shipped. An example of such an article is a porcelain finished stove, especially at the present time, as the trend is to eliminate exposed metal parts of the stove, including nickel, or otherwise finished trimming, and making substantially all parts of the stove porcelain finished. Even if such an article is properly packed in a wooden crate the jars and jolts incident to shipping on a railroad is liable to crack or chip the porcelain by reason of the sudden starting and stopping of the freight cars. Accordingly, the invention contemplates an arrangement wherein the article has no contact with the shipping rack, except in that it rests upon the bottom of the rack, and moreover, a shock absorbing arrangement is provided to protect the article while it is in the rack.

In the accompanying drawings:

Fig. 1 is a horizontal sectional view taken through a freight car showing the manner in which a number of the racks containing articles are loaded and secured in place in the car.

Fig. 2 is a view showing how a plurality of the crates may be secured together in col-

lapsed form while being returned to the shipper.

Fig. 3 is a plan view of a frame which constitutes a part of each rack.

Fig. 4 is an end view showing the frame and the corner sockets which are secured to the frame.

Fig. 5 is an enlarged detail in section taken on line 5—5 of Fig. 3 showing the lock structure.

Fig. 6 is an enlarged detail on line 6—6 of Fig. 3.

Fig. 7 is a plan view of a plate upon which an article to be shipped is placed.

Fig. 8 is an enlarged fragmentary view showing how two of such frames are spaced apart and braced one with respect to the other.

Fig. 9 is an end view of crating set up and holding three articles, such as stoves, arranged vertically.

The rack consists in a plurality of like units one of which is a frame construction in the nature of a platform. This frame is shown in Fig. 3 and is referenced, generally, 1. The frame is made up of side members 2 and 3 which may be of T-section metal for purposes of strength, and end members 4 and 5, which may be of angle metal. A number of cross braces 6 are provided for making the frame rigid. At each corner of the frame is a socket-like member 7 provided with extensions 8 which are secured to the frame as at 9. This socket is shown in section in Fig. 8, and is provided with opposed sockets divided by web 10 which is in turn provided with a relatively small opening 11, the purpose of which will soon be brought out. For the purpose of further strengthening the frame the cross members 12 may be provided, and each socket member may have a projection 13 of angular form for receiving the ends of the members 12, and the members 12 may be tightened and held in position by suitable nuts 14.

Running lengthwise of the frame, and near each edge thereof, is member 15; this member is of channel formation for a portion of its length, as shown in Fig. 6. The channel formation extends from about the point 16 to the point 17 (Fig. 3) so that the channel formation is removed from the ends of the

frame. Moreover, the back wall of the channel is chamfered or cut away and extends beyond the end of the channel formation, as shown at 18, of Fig. 3.

5 A plate 20, as shown in Fig. 7, is designed to be slidably received on a platform, and it fits in the channels as shown in Fig. 3. A stove or other article to be shipped is secured to this plate, and for this purpose the plate 10 is provided with a number of bolt holes 21. Adjacent these bolt holes are hand holes 22 so that an operator can reach his hand through the hand hole and tighten bolts which extend through the bolt holes in the plate and 15 adjacent openings in the stove. In some instances there are bolts or other projections extending downwardly from the stove, and the plate may be provided with openings 23 for providing a clearance for these projections. The openings 23, as shown in Fig. 7, are positioned correctly for a particular type of stove, but it will be understood that these openings can be placed anywhere according to the location of the projections on the 20 stove.

The plate, when in proper position in the frame, is locked with respect to the frame, and preferably this locking device takes the form of a shock absorber. For this purpose 25 the plate may be provided with an opening 24 having oppositely extending narrow portions. Cooperating with this opening is a locking device, as best shown in Figs. 3 and 5. This locking device consists of a bolt 25 slidably mounted in spaced brackets 26 which are secured to the frame. Centrally of the bolt is a fixed shoulder member or washer 27, and on either side of the member 27 and between the brackets are coil springs 28 and 30 28^a. Pinned to one end of the bolt, as shown in Fig. 5 is an arm 29 provided with the locking member 30. This locking member is preferably provided with a knurled handle 31 so that the same can be rotated in the arm, 35 and a spring pressed ball or plunger 32 is carried by the arm which cooperates with recesses 33 in the lock to hold the same in proper position, but which permits turning of the lock when sufficient turning pressure 40 is applied to the handle 31. The lower end of the lock member is provided with a pin 34.

The plate 20 having been moved onto the platform in the channel formation, the lock member 29 is moved down over the plate until 45 the cross pin 34 passes through the opening 24 in the plate, whereupon the lock 31 may be turned to position the pin crosswise of the hole 24 so that the same can not come out. The plate 20 is thus locked in the frame. 50 However, it will be noted that the plate, together with the lock, can reciprocate lengthwise of the frame, which reciprocation is permitted by reason of the springs 28 and 28^a.

Note, in Fig. 3, that the ends of the plate are 55 well within the ends of the frame so that the

plate is free to thus reciprocate. A movement of the plate from right to left with respect to the frame compresses the spring 28, and the reverse movement compresses the spring 28^a, with the two springs tending normally to maintain the plate in the normal position shown.

Fig. 9 shows how a plurality of articles may be arranged one above the other by the use of posts. One frame is placed on the floor 70 of a railroad car, for example, and then a post 40 is placed in each corner socket in a manner shown in Fig. 8. A second frame is then placed on the top of the posts 40, and further posts 41 are placed in the sockets of the 75 second frame, and then a third frame may be placed upon the tops of the posts 41. As shown in Fig. 9, three stoves are placed one above the other; the total height of this arrangement is such that it nicely fits in an ordinary freight car, but of course, if smaller articles are to be shipped, the posts can be made shorter, and any number of the articles 80 can be superimposed one above the other.

Fig. 9 shows how a plurality of articles may be arranged one above the other by the use of posts. One frame is placed on the floor 70 of a railroad car, for example, and then a post 40 is placed in each corner socket in a manner shown in Fig. 8. A second frame is then placed on the top of the posts 40, and further posts 41 are placed in the sockets of the 75 second frame, and then a third frame may be placed upon the tops of the posts 41. As shown in Fig. 9, three stoves are placed one above the other; the total height of this arrangement is such that it nicely fits in an ordinary freight car, but of course, if smaller articles are to be shipped, the posts can be made shorter, and any number of the articles 80 can be superimposed one above the other.

In leading a railroad car with stoves, the 90 stoves are first secured to the plates 20. This may be done any place in the factory, as for example, in the shipping room where the procedure can be efficiently accomplished. Then a set of platform and posts are set up, as 95 shown in Fig. 9, in the corner of a car. In Fig. 1 the car is diagrammatically represented at 50, and at 51 is represented the first tier of crates. The stoves may then be brought in and the plates slid into position on the frames and locked. A second tier of frames represented at 52, is then set up in abutting 100 relation to the first tier and the stoves placed therein. Then a tier 53 is set up in the other corner of the car. This tier is spaced relative 105 to the next adjacent tier and an expansion bolt 54 is placed between the tiers thus separated. For this purpose each socket is provided with a squared opening 40^a for receiving the squared end 40^b of the bolts. This 110 arrangement keeps the bolts from turning and may be expanded by a suitable turn buckle 42. As shown in Fig. 9, it is preferable to use three of these expansion bolts; or in other words, one for each platform. It is 115 not believed necessary to use expansion bolts at the inner ends of the frames, or in other words, adjacent the end of the car, inasmuch as they are abutted against the sides of the car and end of the car, and can not become 120 loose so long as the outer ends are held tightly. The expansion bolt causes the frames to be expanded and rigidly held against the slides of the car. Thus there are three 125 tiers of stoves arranged transversely across the car, which forms one section, which fills one end of the car. The placing of the sections will continue according to the capacity of the car. The other end of the car is filled up in similar manner. As just stated, the 130

stoves are placed in the tier 51 as soon as the tier is assembled. However, the stoves need not be placed in the tiers 51, 52 or 53 until all the tiers are assembled and locked by expansion bolts.

When the car is filled up from each end, to the center, a space is left at the center of the car. Expansion bolts 55 are placed lengthwise of the car and tightened. Preferably an expansion bolt is used for each tier, or, in other words, at each platform. At this point the reason why the channel formation does not extend to the end of the frame becomes apparent. The space left in the center of the car is usually not as wide as the length of the plate 20 upon which the stoves are mounted. The plates, with the stoves mounted thereon, may be taken into this space endwise and then first inserted over the frame or platform angularly without interference by the channel. When the plate is sufficiently overlapped with respect to the frame, the plate and stove can be straightened out with respect to the frame and then slid into place.

It will be understood that all of the platform units are identical so that they can be used at any place, as for example, at the bottom of a tier, at the top of a tier, or as the last tier near the center of the car where the expansion bolts 55 are used. Similarly, all the plates are identical so that they can be used with any platform. Moreover, all of the posts 40 and 41 are identical. This expedites assembly of the cratings and the loading of the car inasmuch as all the units are interchangeable.

After the car is unloaded and the stoves removed from the plates, the plates are then slid back into place on the platforms, and locked in place. The platforms are then packed together, as shown in Fig. 2. The posts and bolts are laid down on each platform. For this purpose each platform is provided with a pair of pocket-like members 45 and 46 having open tops and closed ends, as at 47. The four posts used in conjunction with each platform nicely fit into these members and are held in place; also an extension bolt or two can be placed in with the posts. Upon assembling the frames, as shown in Fig. 2, bolts 48 may be passed through the corner sockets of the platforms by utilizing the small openings 11 in each socket. This holds a number of platforms together so that they can now be shipped back to the original shipper.

The top frame or platform is preferably reversed or turned upside down so that its pockets for holding the posts and bolts are upside down and on the reverse side of the pocket of the next adjacent platform. By doing this the two top platforms arranged face to face hold the posts and bolts in position in the pockets.

It will be noted that each stove, or other

article in no way contacts with any of the crating structure, and that each stove is bolted securely to a plate. The plate and stove are of less length than the frame so that there is free movement back and forth of the stove by the action of the springs in the lock, which arrangement absorbs the shocks incident to the moving and spotting of the railroad car, etc.

It has been found advantageous to discuss and describe the invention with respect to the racking and shipping of stoves. It will, of course, be understood that the invention is applicable to the racking and shipping of articles of various kinds. The articles may be smaller than stoves in which case there will be more articles in a tier, and there may be more tiers arranged transversely of the car; and in case of articles larger than stoves the converse will be true.

The crating is also adapted for storage purposes as, for example, if a dealer desires to keep a number of stoves or other articles on hand in a warehouse. The stoves and racks may be removed from a freight car and stored in the warehouse by setting up the racks in much the same manner as the racks was set up in a freight car. The top platform of the crating, if the same is set up in a car or in a warehouse for that matter, is not used with posts inasmuch as the posts are only used for supporting a platform.

An advantage which exists in the present invention is the manner in which the rack can be set up after the stoves are placed therein and when both ends of the car have been filled leaving a narrow space in the center of the car. A stove or other article can be slipped into place as above described by moving the article lengthwise into the narrow space and giving it a twist and sliding it under a platform. When this is done the posts of this platform need not be as yet in place so that the posts do not interfere with the placing of the stove and the platform. In other words, a plate with its article may be moved across a corner of the platform if there is no post to interfere with this movement. This aids in the filling of the car substantially to the center thereof.

Claims:

1. In a rack, the combination of a plurality of platforms each having a socket at each corner, removable posts adapted to be secured in said sockets whereby a plurality of said platforms may be arranged in vertical and spaced relation, and means removably received on each platform, the said means being adapted to hold an article to be shipped in the rack and locking means for holding the removable means in place.

2. In a rack, the combination of a plurality of platforms each having a socket at each corner, posts adapted to be secured in said sockets whereby a plurality of said platforms

may be arranged in vertical and spaced relation, means slidably received on each platform, the said means being adapted to hold an article to be shipped in the rack, and a shock absorbing device which permits relative movement between each platform and its respective means to cushion the article from shocks.

3. A collapsible permanent rack for shipping and the like, which consists in a plurality of platforms each adapted to hold an article to be shipped, post members removably secured to this platform for holding a plurality of said platforms in vertical and spaced relation, means on each platform for receiving a plurality of said posts when the crating is collapsed, and means for securing a plurality of said platforms in direct superimposed position.

4. A collapsible permanent rack for shipping and the like, which comprises a platform adapted to receive an article, posts detachably connected to the platform and adapted to hold a second similar platform above the said article, said second platform being adapted to hold an article to be shipped, means upon at least one of the platforms for receiving and carrying the posts in collapsed position, and means for securing the platforms together for shipping, and otherwise handling, in collapsed position.

5. In a permanent rack, a platform, a plate-like member adapted to be secured to an article to be shipped, or similarly handled, means on the platform for detachably holding said plate, including a shock absorbing device which permits relative movement between the platform and the plate to protect the article on the plate.

6. In a permanent rack, a platform, a plate-like member adapted to be secured to an article to be shipped or otherwise handled, channel members on the platform for slidably receiving the plate, a lock for locking the plate member on the platform, and a spring shock absorbing device in conjunction with the lock which permits relative movement between the plate and the platform under spring action to protect the article on the plate.

7. In a permanent rack, a platform, channel guideways on the platform, a plate adapted to be secured to an article to be shipped or otherwise handled, said plate being adapted to be received in the channel guideways on the platform, a locking device on the platform for locking the plate thereon, said locking device being carried by opposed coil springs whereby the lock and plate may move relative to the platform under the action of the springs to absorb shocks in shipping and protect the article on the platform.

8. A permanent and collapsible rack for shipping and the like purposes, which comprises a plurality of identical platforms, a

plurality of identical posts for detachable connection with the platforms whereby a plurality of such platforms may be arranged in vertical and spaced relation, means on each platform for receiving an article to be shipped or otherwise handled, said rack being adapted to be collapsed with the platforms superimposed one upon another in direct abutting relation, and means on each platform for receiving and holding the posts in this collapsed condition.

9. A permanent and collapsible rack for shipping and the like purposes, which comprises a plurality of identical platforms, a plurality of identical posts for detachable connection with the platforms whereby such a plurality of platforms may be arranged in vertical and spaced relation, means on each platform for receiving an article to be shipped or otherwise handled, said rack being adapted to be collapsed with the platforms superimposed one upon another in direct abutting relation, and means on each platform for receiving and holding the posts in this collapsed condition, and means for securing a plurality of said collapsed platforms together for shipment of the rack without articles.

10. A permanent collapsible rack for shipping or otherwise handling articles, comprising a plurality of substantially identical platforms, a member at each corner of each platform provided with upper and lower sockets, posts adapted to be secured in the sockets whereby a plurality of said platforms may be arranged in vertical and spaced relation for holding articles to be shipped, each corner member having a relatively small aperture connecting the said upper and lower sockets, said platforms, when the rack is collapsed, being adapted to be superimposed one upon another in direct abutting relation, and means extending through the said relatively small apertures for holding a plurality of the platforms together.

11. The method of shipping or otherwise handling articles, which comprises the setting up of a collapsible rack, attaching an article to be shipped to a detachable portion of the rack, and then placing the article in the set-up rack by securing the detachable portion of the rack which holds the article to the rack.

12. The method of shipping or otherwise handling articles, which comprises the setting up of collapsible rack which includes a plurality of similar platforms, securing each article to a detached portion of the rack and then placing each detached portion of the rack, which holds an article, to one of the said platforms.

13. The method of shipping articles in a freight car, which consists in setting up permanent and collapsible rack transversely across the end of the car, placing the articles in the rack and then securely fixing the crat-

ing in the car by utilizing an expansion bolt between two units of the rack arranged transversely across the car to hold the rack tightly against the sides of the car.

5 14. The method of shipping articles in a freight car, which consists in setting up collapsible rack for holding the articles transversely across one end of the car, and securely fixing the rack by utilizing an expansion bolt
10 to tighten the rack against the sides of the car, filling up the car from each end toward the center with similar transversely arranged rack and transverse expansion bolts, and then inserting longitudinal expansion bolts be-
15 tween adjacent crating near the center of the car, and tightening the bolts to hold the rack against the end of the car.

In testimony whereof I affix my signature.
